(57) **CLAIM**

The ornamental design for a drill bit penetration measurement system control housing, as shown and described.

DESCRIPTION

FIG. 1 is a front perspective view of a drill bit penetration measurement system control housing;

FIG. 2 is a rear perspective view of the drill bit penetration measurement system control housing of FIG. 1;

FIG. 3 is a front view of the drill bit penetration measurement system control housing of FIG. 1;

FIG. 4 is a rear view of the drill bit penetration measurement system control housing of FIG. 1;

FIG. 5 is a left side view of the drill bit penetration measurement system control housing of FIG. 1;

FIG. 6 is a right side view of the drill bit penetration measurement system control housing of FIG. 1;

FIG. 7 is a top view of the drill bit penetration measurement system control housing of FIG. 1; and,

FIG. 8 is a bottom view of the drill bit penetration measurement system control housing of FIG. 1.

The broken lines in the drawing indicate environmental structure and form no part of the design to be patented.
